MARIO ROFFINO, OF NEW YORK, N. Y.

CONCRETE BLOCK CONSTRUCTION.

Application filed December 12, 1922. Serial No. 606,426.

To all whom it may concern:

Be it known that I, MARIO ROFFINO, a subject of the King of Italy, and a resident of the city of New York, borough of Manhattan, in the county and State of New York, have invented a new and Improved Concrete Block Construction, of which the following is a full, clear, and exact description.

This invention relates to a concrete block construction. In building construction where concrete blocks are used it is highly important that the work be carried on with the utmost expedition and ease, and since the blocks are in most cases provided already formed of the proper dimensions, it is also highly desirable that the blocks be capable of assembly not only with ease but requiring the minimum amount of skill on the part of the person assembling them. It is, furthermore, desirable that the blocks, after being assembled, can be very firmly locked together so that the structure will be rigid and will remain rigid indefinitely. It is also desirable that the construction can be disassembled as quickly and easily as it can be assembled.

It is, therefore, the object of my invention to provide a construction and form of block and co-operating elements for tying the blocks together in a structural unit so as to achieve the above-mentioned desirable features in the blocks and in their manner and method of assembly and disassembly.

The invention is illustrated in the drawings, of which—

Figure 1 is a partial perspective view of a plurality of blocks tied together to form a wall construction.

Fig. 2 is a transverse vertical section through the blocks.

Fig. 3 is a longitudinal vertical section through the blocks.

Fig. 4 is a section taken on the line 4—4 of Figs. 1 and 3.

The form of the invention shown in the drawings is a preferred form, although it is understood that modifications in the construction and arrangement of the parts and in the character of the materials used may be adopted without departing from the spirit of the invention.

Each block used to form any desired structural unit comprises a concrete member having longitudinal side walls, 1 and 2, and transverse end walls, 3 and 4, all of which

extend the full depth of the block. Intermediate the end walls 3 and 4 and extending across between the side walls 1 and 2 in each block are a pair of reinforcing strengthening bars or rods, 5 and 6, disposed respectively at the upper and lower edges of the walls 1 and 2 and each extending only part way inwardly from their respective edges. As shown in the drawings, these rods 5 and 6 are approximately one-third the depth of the block. The upper edges of the side walls 1 and 2 are provided with grooves 7 and 8, and the lower edges of the side walls 1 and 2 are provided with ribs 9 and 10. The ribs 9 and 10 are slightly smaller in dimensions than the grooves 7 and 8 so that when the ribs of one block lie in the grooves of another there will be some space left over. In joining the blocks it is intended to place a certain amount of cement in the grooves, and then when the ribs of the related block are pressed into the grooves the concrete is forced into intimate contact with the ribs to form a tight locking joint between the two blocks. Each block is provided with reinforcing members, such as 11, which may be in the form of wires or rods extending around the periphery of the block adjacent the top and bottom edges.

The end walls of each block, as shown particularly in Fig. 4, are provided with vertical grooves, 12 and 13, each preferably semi-circular in shape and adapted when the blocks are disposed in an abutting relation to form a circular passageway leading from the top to the bottom of each block and connecting the grooves 7 and 8 in one block with corresponding grooves in the block above. When one block is placed on another in close relation with a second block, the cement in the grooves, forced out of the grooves by the rods engaged in the grooves, will be forced partly up the passageway formed by the grooves 12 and 13, and this key of cement will tend more effectively to lock the blocks together.

It will be noted from a consideration of Fig. 1 that the blocks are disposed in an overlapping or staggered relation. In other words, the end walls of adjacent blocks on one level lie respectively over and under the transverse strengthening bars, such as 5 and 6, of blocks in the adjacent level, and the strengthening bars of this same block lie adjacent the abutting end sections of the blocks in the adjacent level.

In order not only to lock blocks in the same level together but to lock the blocks in one level firmly in their proper relation with the blocks in the levels immediately above and below, I have provided a combination of locking elements which enables the blocks to be very quickly assembled and very firmly locked together. This combination of elements is such as requires practically no particular skill on the part of the workman who is assembling the wall or other construction. To this end I provide the end walls of each block with a plurality of apertures through which hooked bolts, such as 14, extend. These bolts have, in the well-known manner, a hooked formation on one end and are provided with a clamping nut 15 on the other end. Beneath the head or nut 15 and passing around the end of the bolt 14 is a link 16. This link extends downwardly across the joint between one level of blocks and the row of blocks immediately below it. The lower end 19 of the link 16 passes between a bolt head 17 and a stationary lug or projection 18, although the link 16 is smaller than the passageway between these two projections. However, the wedge member 20 is forced between the links 16 and the projection or lug 18 and very firmly clamps the link 16 in position. Similarly, the hooked end 14 of the bolt is engaged by a wedge member 21 (see Figs. 3 and 4), and this wedge member when driven in will clamp the bolt 14 to hold the end walls of abutting blocks together. Therefore, looking at Fig. 2 and the main end of Fig. 3, it will be seen that the abutting end walls are held together by the action of a wedge member, and the link connecting one of these end walls with the reinforcing rod of the block bolt is also firmly clamped by means of the action of a wedge member, and in this manner two blocks in one level are held firmly together and both are very firmly tied to the block immediately below as well as to the block immediately above. In view of the fact that the hooked bolts 14, the links 16, the wedge members 20 and 21 and the other parts can all be made of stock material, ready for use, it will be observed that the assembly of this construction is an exceedingly simple matter, requiring very little skillful knowledge on the part of the workmen assembling it.

It will be noted in Fig. 3 that the lower pair of blocks, marked A, have their two end walls 3 and 4 abutting. These end walls are tied above, as shown in the figure, to the reinforcing rod 6 of a block in a row, marked B, immediately above the first mentioned blocks. It will be noted that the ends 3 and 4 of the blocks in the lower level are tied together by a hooked bolt 14 clamped by a wedge member 21, and that a link 16 extends downwardly across the joint be-

tween the two levels of blocks and is engaged between members 17 and 18 and held in this engagement by a wedge member 20. The member 17 is in the form of an ordinary bolt, the other end of which is provided with a clamping nut 22.

In other words, to tie the abutting ends of two blocks to a block in another level requires a link extending across between the two levels of blocks; requires projections on the ends of the blocks; and requires wedge members to clamp the link to the projections. It also requires a hooked bolt extending between the ends of adjacent blocks in one level, and a wedge member to clamp said bolt in position to hold the abutting ends together.

It will be clear from a consideration of the above description that the manner of connecting the ribs and end walls of the blocks can be employed in other constructions than concrete block constructions, wherever a plurality of adjacently disposed walls are to be tied together.

What I claim is:—

1. A block construction involving a plurality of levels of concrete blocks arranged in a staggered relation, each of said blocks including end and side walls and intermediate strengthening ribs, means for clamping the end walls of adjacent blocks in the same level together and means connecting the end walls of adjacent blocks in one level with an intermediate strengthening rib of a block in an adjacent level.

2. A concrete construction which includes a pair of blocks each having an intermediate strengthening rib, said blocks arranged in a staggered relation with the end wall of one block disposed adjacent the strengthening rib of another block in an adjacent level, the surface of the end wall and the strengthening rib being alined in the same plane, a projection on the end wall, a link extending from said projection across the joint between the wall and the surface of the strengthening rib, a pair of projections on the strengthening rib between which the link passes, and a cam-shaped clamping member disposed between the link and one of said projections to clamp the end of the link and hold the two surfaces in alinement.

3. A concrete block construction which includes a pair of blocks in one level with their end walls abutting, a hooked bolt extending through the wall having a head on one end, a wedge member clamped between the hooked end of the bolt and the other wall to hold the two walls together, a link disposed beneath the head of said hooked bolt, another block in a different level, a strengthening rib intermediate the end of said block, said rib alined with the end walls of the first-mentioned blocks, a link extending from the hooked bolt across the surface of

- the strengthening rib, a pair of projections on said rib between which the end of the link passes, and a wedge member between the link and one of said projections to clamp the link in position and hold the blocks together.
4. A concrete block which comprises end and side walls and a strengthening rib extending across between the side walls intermediate the length of the block, said rib having a depth less than that of the block and a thickness equal to approximately twice the thickness of the end walls.
- 10 5. A concrete block comprising end and side walls, a transverse strengthening rib extending between the side walls having a thickness twice that of the end walls and a depth approximately equal to one-third the depth of the block.
- 15 6. A joint construction for a plurality of walls, which includes a wall disposed in one level, a pair of walls disposed in an adjacent level, said pair of walls abutting the first-mentioned wall, means for clamping said pair of walls together, and means connecting 25 one of said pair of walls with the first-mentioned wall.
7. A joint construction for a plurality of walls, which includes a single wall disposed in one level, a pair of walls abutting each 30 other and adjacent the first-mentioned wall, a projection on one wall, a link extending through said projection across the joint between said wall and the adjacent wall, a pair of projections on said last-mentioned wall 35 between which the link passes, and a cam-shaped clamping member disposed between the links and one of said projections to clamp the end of the link and hold the two surfaces in alinement.

MARIO ROFFINO.
